GEORGE FARRELL, OF WEST SOMERVILLE, MASSACHUSETTS, ASSIGNOR
TO M. W. CARR & COMPANY, OF WEST SOMERVILLE, MASSACHUSETTS,
A FIRM.

EXTENSIBLE BELT OR GIRDLE.

SPECIFICATION forming part of Letters Patent No. 758,240, dated April 26, 1904.

Application filed June 20, 1903. Serial No. 162,344. (No model.)

To all whom it may concern:

Be it known that I, GEORGE FARRELL, of West Somerville, Middlesex county, Massachusetts, have invented certain new and useful 5 Improvements in Extensible Belts or Girdles, of which the following is a full, clear, and exact description.

My invention relates to improvements in belts and girdles, and especially to such devices which are of an ornamental character; and the object of my invention is to produce a belt or girdle which may be made in any suitable or approved design and which while having the characteristics of a solid or non-extensible girdle will yet be sufficiently elastic to fit waists of different sizes and be extensible to a considerable extent.

Another object of my invention is to construct and arrange the extensible portions of the belt or girdle so that such portions will be hidden from view and will not, therefore, detract from the ornamental character of the device.

Still other objects of my invention are to make the device simple, strong, and durable.

With these ends in view my invention consists of certain features of construction and combinations of parts which will be hereinafter described and claimed.

Reference is to be had to the accompanying drawings, forming part of this specification, in which similar figures of reference refer to similar parts throughout the several views.

Figure 1 is an inside elevation of the extensible portion of a girdle or belt, showing my improvements, the structure being shown in its contracted position. Fig. 2 is a view similar to Fig. 1, but with the belt extended; and Fig. 3 is a longitudinal section on the line 3—3 of Fig. 2.

In carrying out my invention I use the ordinary body portion 10 of a belt or girdle, which in the present instance happens to be in the form of parallel chains, but which obviously may be of almost any design. I use this body portion also, by preference, in connection with the ordinary buckle-plate 11, which is of an ornamental character and which

while it has no mechanical function in connection with the extensible features of the belt 50 yet serves as a shield to hide the said extensible portions, and is therefore made in combination with the same.

To the back of the plate 11 I secure a base-plate 12, and rigid on the inside of the base-plate is a second plate 12^a, which to all intents is a part of the base-plate. Projecting inwardly from the base-plate, near the end portions thereof, are keepers 13, through which slide the opposed plates 14, which have 60 ears 15, connecting with the body portion 10 of the belt; but obviously this connection may be made in any usual manner. The inner ends of the slide-plates 13 have stops 16, which by striking the keepers 13 limit the outward 65 movement of the slide-plates. Each slide-plate is connected with a pair of flexible extensible springs 17, the opposite ends of the springs being secured to bosses 18 on the plate 12^a. By having the springs 17 overlapping, 70 as described, and with the springs connecting the inner edge of one slide-plate with an opposed portion of the base-plate the device is brought into very compact shape and the pull of the springs is very effective.

It will be seen that the tension of the springs serves to pull the slide-plates 14 together and so shorten the belt; but they can be pulled apart, if necessary, to make the belt longer. It will be observed also that this extensible 80 feature of the belt is hidden behind the buckle-plate 11 and, further, that the details of the structure can be changed considerably without affecting the principle of the invention.

I wish to call attention further to the fact that by having the extensible part of the belt located midway of the belt the structure is properly balanced and the strain equally distributed, so that the belt or girdle will retain 90 its normal shape even though extended.

Having thus described my invention, what I claim as new, and desire to secure by Letters Patent, is—

1. A belt or girdle comprising a supporting- 95 plate, slide-plates movable on the supporting-

plate, keepers secured to the supporting-plate and acting to guide the slide-plates, and springs on the inner ends of the slide-plates arranged to project under the opposed slide-plate and adapted to be secured to the supporting-plate on the other end.

2. An extensible belt or girdle comprising a shield or cover-plate, a supporting-plate rigidly fastened to the back of the shield or cover-plate, said supporting-plate having inwardly-projecting keepers thereon, slide-plates movable through the keepers back and forth in relation to each other, a body portion connected to the outer ends of the slide-plates,

means for limiting the movement of the slide-plates, and extensible springs crossing each other longitudinally of the spring-plate, each set of springs being attached to the inner end of a slide-plate and to the supporting-plate, as set forth.

20 In witness whereof I have signed my name to this specification in the presence of two subscribing witnesses.

GEORGE FARRELL.
